SHEET SLITTING MACHINE

Lyman L. Jones, Seattle, Wash., assignor to American Can Company, New York, N. Y., a corporation of New Jersey

Application February 25, 1942, Serial No. 432,353

9 Claims. (Cl. 164—61)

The present invention relates to sheet slitting machines and has particular reference to detecting and discarding out-of-square sheets as they pass through the machine.

In the container or can making industry metallic sheets, such as for example, tin plate or the like, are trimmed and cut into blanks from which can bodies are formed. These sheets as they come from the plate mill are of such a dimension that a predetermined number of body blanks of a given size may be cut from each sheet. The sheets are often out-of-square and hence one or more of the blanks when cut from such a sheet may be under size to such an extent that they cannot be used. If such defective blanks are not segregated from the good or full size blanks they cause trouble in subsequent operation machines that prepare and form the blanks into can bodies.

The instant invention contemplates overcoming this difficulty by providing devices which gauge the sheets prior to their being cut and which detect out-of-square sheets and discard them from the machine.

An object therefore of the invention is the provision in a sheet slitting machine of devices wherein sheets passing through the machine are gauged for out-of-squareness prior to being cut and if found defective, are discarded from the machine so that they may be used for other purposes.

Another object is the provision of such a machine wherein the steps of detecting and discarding defective sheets are effected by electrically operated elements so that the operation is entirely automatic and accurate, thereby eliminating the human judgment factor of inspection.

Another object is the provision of a tandem machine wherein the sheets are gauged and electrically detected prior to their being cut lengthwise and again prior to their being cut transversely of the sheet so that a finished blank will be true to size and square on all edges.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a sheet slitting machine embodying the instant invention, with parts broken away, the view also showing a

plurality of sheets and blanks passing through the machine;

Fig. 2 is a wiring diagram of the electric apparatus used in the machine;

Fig. 3 is a longitudinal section taken substantially along the line 3—3 in Fig. 1, with parts broken away;

Fig. 4 is an enlarged side elevation of one of the movable gauging devices used in the machine, the view being taken substantially along a plane indicated by the line 4—4 in Fig. 1, with parts broken away;

Fig. 5 is a top plan view of the device illustrated in Fig. 4, with parts broken away;

Fig. 6 is a view similar to Fig. 4 and illustrating one of the fixed gauging devices used in the machine, the view being taken substantially along a plane indicated by the line 6—6 in Fig. 1, with parts broken away;

Fig. 7 is an enlarged sectional detail taken substantially along the line 7—7 in Fig. 1, with parts broken away;

Fig. 8 is a transverse section taken substantially along the line 8—8 in Fig. 1, with parts broken away;

Figs. 9 and 10 are enlarged sectional details taken substantially along the line 9—9 in Fig. 1, with parts broken away, the views showing certain of the movable parts of the machine and a blank passing through the machine in different positions; and

Fig. 11 is a schematic perspective view showing how the various rotating parts of the machine are driven.

As a preferred embodiment of the invention the drawings illustrate principal parts of a tandem slitting machine of the character disclosed in United States Patent 1,841,426, issued January 19, 1932, to J. C. Balletti, on Body blank sorting apparatus for plate slitting machines.

In such a machine metal sheets A (Fig. 1) are conveyed longitudinally of the machine and are trimmed and cut into two smaller size sheets B. These sheets B are then conveyed transversely of the machine at right angles to their first path of travel, and are again trimmed and cut into can body blanks C. This completes the slitting operations and accordingly the blanks are conveyed to a suitable place of deposit.

The sheets A enter the machine from any suitable source of supply of such sheets, pass along an inclined runway which includes a plurality of rails 11 (Figs. 1 and 3). These rails are secured to a table 12 which forms a continuation of the rails. The table is formed on an adjust-

able sub-frame 13 mounted on a transverse pivot pin 14 carried in a base 15. The outer ends of the rails are braced by a connecting bracket 16 and by a pair of angle irons 17 which extend from the bracket to the base.

The sheets A are propelled along the runway by an endless chain conveyor 18 (see also Fig. 11) having feed dogs 19 secured thereto at spaced intervals. The chain operates over a driving sprocket 21 and over a plurality of idler sprockets 22. The idler sprockets 22 are mounted on cross shafts 23 journaled in bearings formed in the sub-frame 13 and in a guard bracket 24 secured to the rail connecting brackets 16.

The driving sprocket 21 is mounted on a drive shaft 26 which is journaled in bearings 27 formed in the machine base 15. This drive shaft constitutes the main driving shaft of the machine and is rotated in any suitable manner.

As the conveyor 18 is thus driven by the drive sprocket 21, the dogs 19 on the chain engage behind the sheets A placed on the runway and propel them forwardly along the runway rails 11. The sheets are guided along a straight line path of travel by a pair of spaced and parallel guide rails 29 which are formed on the outer runway rails 11.

The conveyor 18 propels the sheets A toward a plurality of cooperating upper and lower trimming and slitting rotary cutters 32 which are located adjacent the inner edge of the table 12 so that the sheets to be cut will pass between them. These cutters are mounted on a pair of spaced and parallel horizontal shafts 33, 34 (see also Fig. 11) which are journaled in bearings 35 formed in the sub-frame 13. The shafts extend beyond the bearings on one side of the sub-frame and carry meshing gears 36, 37 so that the cutters will rotate in unison.

The lower cutter shaft 34 is rotated by a sprocket 38 which is mounted on the shaft adjacent the gear 37. This sprocket is driven by an endless driving chain 39 which operates over a sprocket 41 on the main driving shaft 26. The chain also operates over and drives a sprocket 42 (see also Fig. 7) which is mounted on a cam shaft 43 journaled in bearings 44 formed in the sub-frame 13. This is a usual slitter construction.

When a moving sheet A propelled by the conveyor 18 is fully on the table 12 it is gauged for squareness just before it passes between the cutters 32. This gauging is brought about by a pair of fixed gauges 52 which are disposed along one side of the machine as viewed in Fig. 1 and 55 by a flexible gauge 53 which is located along the opposite side of the machine. The fixed gauges 52 (see also Fig. 6) depend from brackets 55 which are secured to a gauge bar 56 formed on a gauge slide 57 located in a slideway 58 of 60 a slide bracket 59 bolted to the sub-frame 13.

The gauge slide 57 carries an actuating pin 62 which extends down through the bottom of the slide bracket 59. The lower end of this pin 65 operates in a cam groove 64 of a barrel cam 65 mounted on the outer end of the horizontal cam shaft 43.

Thus as the main shaft 26 rotates the cam shaft 43 and the cam 65 carried thereon, the latter at the proper time shifts the slide 57 and its gauge bar 56 inwardly toward the moving sheet A as it passes across the table 12. This movement of the gauge bar brings the vertically disposed fixed gauges 52 into position closely 70 75

adjacent the longitudinal edge of the moving sheet A.

At the same time the flexible gauge 53 is shifted toward the opposite edge of the moving sheet. 5 This flexible gauge includes a vertical roller 66 (see also Figs. 4 and 5) which is carried on the outer end of a gauge arm 67 mounted on a pivot pin 68 secured in a gauge block 69 bolted to a gauge bar 71. A compression spring 72 interposed between the gauge arm 67 and the gauge block 69 maintains the arm extended in the direction of the passing sheet A. The arm adjacent the pivot pin 68 is formed with a stop lug 73 which strikes against the gauge block 69 and thus limits the outward travel of the arm.

The gauge bar 71 on which the flexible gauge unit 53 is mounted, is formed integrally with a horizontal gauge slide 76 (see also Fig. 7) which moves in a slideway 77 of a slide bracket 78 bolted to the sub-frame 13. The slide carries a depending actuating pin 79 which extends down through a slot 81 in the bracket. The lower end of this pin operates in a cam groove 82 of a barrel cam 83 mounted adjacent the sprocket 42 on the cam shaft 43. This cam and slide construction is identical with the opposite cam 65 and slide 57 and they are actuated simultaneously by the rotation of the cam shaft 43.

Hence the rotating cam 83 shifts its gauge slide 76 and the gauge bar 71 inwardly toward the sheet A simultaneously with the movement of the opposite gauge bar 56. During this movement the roller 66 of the flexible gauge unit 53 engages against the adjacent edge of the passing sheet A and shifts the sheet transversely of the table 12 and into engagement with the two fixed gauges 52. Thus there is brought about a momentary three point contact with the sheet which aligns the longitudinal edge at the right of the sheet as viewed in Fig. 1, with the two fixed gauges 52.

If the sheet is square, as it should be, the longitudinal edge at the left of the sheet as viewed in Fig. 1 will be parallel with the opposite edge. 48 If it is out of square this edge at the left of the sheet will be out of parallel with the opposite edge and when the sheet is out of square beyond certain limits, which cannot be compensated for by trimming the sheet, it is a defective sheet and is discarded from the machine.

Detection of a defective sheet is brought about by a pair of spaced detecting elements 86 (Fig. 1) which are located on the gauge bar 71, one on each side of the flexible gauge unit 53. Each of these detecting elements 86 includes a roller 87 which is disposed adjacent the edge of the passing sheet A and which is carried on one leg of a bell crank lever 88. The bell crank levers are mounted on pivot pins 89 which are carried in the gauge bar 71. The other leg of each of the bell crank levers engages against the movable element of a pair of normally open electric switches 91 which are secured to the gauge bar 71.

The switches 91 operate an electric solenoid 92 having a movable core 93 which connects with an arm 94 (see also Fig. 8) mounted on a cross shaft 95 disposed adjacent the cutters 32. The shaft carries a plurality of gate fingers 96 to deflect the sheets, after being cut, into a discard bin 97 or onto a subsequent operation conveyor in accordance with the sheet being gauged and detected.

The normal position of the gate fingers 96 is that shown in Fig. 3 in which the fingers are

above the path of travel of the sheets B as they come from the cutters 32. In this position of the fingers the good sheets, i. e., those which are in square, pass under the fingers for a subsequent cutting operation. When an out-of-square sheet A is detected, the gate fingers 96 are lowered to a position below the path of travel of the good sheets and this deflects the sheets B as they leave the cutters and directs them into the discard bin 97.

This operation of the gate fingers 96 is brought about by the combined action of both of the detector switches 91 on the gate solenoid 92. When a sheet A is square, both detector elements 86 will engage the sheet edge simultaneously and thus will close both of the detector switches 91. When both switches are closed the gate solenoid is energized to shift the gate fingers into their normal position.

When a sheet A is out-of-square, the edge of the sheet adjacent the detector elements 86 will be inclined or tapered and hence only one of the elements will engage the sheet. Thus only one of the detector switches 91 will be closed. This condition will de-energize the gate solenoid 92 and thus shift the gate fingers 96 into a sheet deflecting position as mentioned above. This energizing and deenergizing of the gate solenoid is brought about by a plurality of electric circuits which will now be explained.

Reference should be made to the portion of the wiring diagram at the left in Fig. 2. In this portion of the diagram the two detecting switches 91 are connected in series by a wire 101. The first of the switches is connected by a wire 102 to a main lead wire 103. The lead wire connects with a generator 104 which supplies the electric energy for the circuits. The second of the detector switches 91 is connected by a wire 105 to a solenoid relay 106 having a movable core 107. The relay is connected also by a wire 108 to a main return wire 109 which connects with the generator 104.

When both of the detector switches 91 are closed, by the detection of a square sheet A, electric energy from the generator 104 flows along the circuit just explained and energizes the solenoid relay 106. Energizing of this relay shifts its movable core 107 and thus closes two normally open switches 111, 112 which are connected to the core. Switch 111 is part of a holding circuit which includes a cam operated normally closed switch 113.

Since the greater number of sheets which pass through the machine are good sheets, the holding circuit is incorporated in the apparatus to hold the gate fingers 96 in their normal position to prevent shifting of the gate fingers for each sheet. For this purpose one side of the cam switch 113 is connected by a wire 114 to the lead wire 102. The other side of the cam switch is connected by a wire 115 to the switch 111. This switch 111 is also connected by a wire 116 to the wire 105.

The cam switch 113 is mounted on a side of the subframe 13 adjacent the gauge slide cam 83 (Fig. 7) and is actuated by a cam projection 118 formed on the slide cam. This cam projection 118 momentarily opens the cam switch 113 just prior to the closing of the detector switches 91. The cam switch 113 closes again before the detector switches open and thus electric energy passing along this holding circuit holds the solenoid relay 106 energized.

The switch 112 forms a part of a gate solenoid circuit which includes the gate solenoid 92. One side of the switch is connected by a wire 121 to the lead wire 102. The opposite side of the switch is connected by a wire 122 to the gate solenoid 92. The solenoid is also connected by a wire 123 to the return wire 108.

Hence when the switch 112 is closed by the energizing of the relay 106, electric energy from the generator 104 passes along this solenoid circuit and energizes the gate solenoid 92. It is this energy that maintains the solenoid 92 energized and thus maintains the gate fingers 96 in their normal position as long as good sheets A are passing through the machine.

When an out-of-square sheet is encountered and one of the detector switches 91 remains open when the cam switch 113 opens, all circuits are immediately broken and the gate solenoid 92 is de-energized. It is this action that shifts the gate fingers 96 into sheet deflecting position, as hereinbefore explained.

The good or in-square sheets B as they come from the cutters 32 fall upon an auxiliary or transverse conveyor 131 (Figs. 1, 3, 8 and 11) having spaced feed dogs 132 which propel the sheets B transversely through the machine, at right angles to their former path of travel. Such latter travel is for a blank cutting operation, as hereinbefore mentioned. The sheets B are guided into position on the conveyor by a curved guide rail 133 and a straight stop rail 134. These guide rails form part of a runway which includes a plurality of horizontal rails 135 on which the sheets B are supported.

The runway rails 135 are secured to a horizontal table 136 which is a continuation of the runway. This table is formed on a sub-frame 141 mounted on a bar 142 secured in a machine base 143 located adjacent the machine base 15.

The conveyor 131 operates over a driving sprocket 145 and a pair of idler sprockets 146. The idler sprockets 146 are mounted on cross shafts 147 journaled in bearings formed in the sub-frame 141 adjacent its inner edge and in a bracket 148 secured to the outer ends of the runway rails 135. The driving sprocket 145 is mounted on a drive shaft 151 (see also Fig. 11) journaled in bearings 152 in the machine base 143.

The drive shaft 151 is driven by a sprocket 154 which is mounted on the shaft and which is rotated by an endless driving chain 155. The chain 155 is driven by a sprocket 156 mounted on a horizontal shaft 157 journaled in a bearing bracket 158 (Fig. 8) bolted to the machine base 15. The shaft 157 carries a bevel gear 161 which meshes with and is driven by a bevel gear 162 mounted on the main drive shaft 26. By means of this connection with the main drive shaft, the transverse conveyor 131 is actuated in timed relation with the longitudinal conveyor 18 hereinbefore mentioned.

The driving chain 155 also operates over and drives a cam shaft sprocket 165 and a cutter shaft sprocket 166. The cutter shaft sprocket 166 is mounted on the lower of a pair of spaced, parallel cutter shafts 167, 168 located adjacent the inner end of the table 136. These shafts are journaled in bearings 169 formed in the sub-frame 141 and are rotated in unison by meshing spur gears 171 mounted on the outer ends of the shafts. The shafts carry a plurality of spaced cooperating cutter wheels 172 between which the sheets B are

propelled by the conveyor 131 for trimming the outer edges of the sheets and for cutting the sheets transversely into the blanks C hereinbefore mentioned. These cutting wheels and their manner of operation are identical to the cutters 32.

The cam shaft sprocket 165 is mounted on a horizontal cam shaft 175 which is journaled in bearings formed in the sub-frame 141. This cam shaft carries a pair of gauge actuating cams 176 which are located one on each side of the sub-frame 141 and which are identical with the gauge cams 65, 83 hereinbefore mentioned. The gauge cams 176 actuate a pair of oppositely disposed gauge slides 177, 178 (Fig. 1) which operate in horizontal slideways 179 formed in slide brackets 181 bolted to the sides of the sub-frame. The gauge slide 177 carries a gauge bar 184 while the slide 178 carries a gauge bar 185. These gauge bars are located on opposite sides and adjacent the path of travel of the sheets B moving across the table 136.

The gauge bar 185 carries a fixed gauge pin 186 located in a block 187 secured to the bar. The opposite gauge bar 184 carries a flexible gauge element 188 which is identical to the flexible gauge element 53. These gauge elements 186, 188 cooperate with a pair of fixed gauge elements 191 (see also Figs. 9 and 10) located adjacent the cutter wheels 172. These gauge the sheets B with a four point contact.

The gauge elements 191 are of curved configuration and are mounted on a cross shaft 194 located above and parallel with the upper cutter shaft 168. The ends of the cross shaft are carried in bearing brackets 195 which are secured to the sub-frame 141.

The gauge elements 191 are held under spring tension by a spring 196 (Fig. 10) having one end secured to one of the bearing blocks 195 and having its opposite end hooked into a lever arm 197 which is carried on the cross shaft 194. These gauge elements extend downwardly around the rear of the upper cutter shaft 168 and their lower ends project inwardly of the cutter wheels and terminate in the path of travel of the sheets B moving toward the cutters. These lower ends of the elements are formed with gauge surfaces 198.

Hence as a sheet B moves along the table 136 toward the cutter wheels 172, its leading edge first engages the gauge surfaces 198 of the two gauge elements 191. It will be remembered that this leading edge has been cut square by the cutters 32 as the sheet passed longitudinally through the machine and thus this edge is used to bring the sheet into square just prior to its being cut transversely by the cutter wheels 172.

The sheet B being propelled by the conveyor dogs 132 is pushed against the gauge elements 191, against the resistance of the tension spring 196 and this resistance permits the sheet to turn slightly as it moves forwardly until both gauge elements are engaged by the sheet edge. When both elements are engaged the sheet edge is parallel with the cutter shafts 167, 168 and is therefore in square.

Simultaneously with this squaring of the sheet B, the side gauge bars 184, 185 move in toward the sheet. During this movement of the gauge bars the flexible gauge element 188 engages the sheet along the adjacent side edge and pushes the sheet across the table into engagement with the fixed gauge 186 on the opposite gauge bar 185. Thus the sheet is located by a four-point contact which prepares the sheet for cutting.

While a sheet B is thus being located for cut-

ting into blanks C, its side edges which thus far have not been trimmed, are detected for out-of-squareness with the front and rear edges. This detecting is effected by four detector elements 201 which are identical to the detector elements 86 hereinbefore mentioned. These elements like the elements 86, include rollers mounted on lever arms which actuate normally open electric switches 202 carried on the gauge bars 184, 185. There are two of these switches on each gauge bar and they are located one on each side of the gauge elements 186, 188.

The detector elements 201 engage against the side edges of the sheet being gauged and close the switch when these edges are square with the front and rear edges of the sheet. If one or both of the sheet side edges are tapered or inclined out-of-square beyond a predetermined limit, one or more of the switches will not be closed and hence the sheet will be detected as an out-of-square sheet and will be discarded.

Discarding of an out-of-square sheet is brought about by a gate 205 (Fig. 8) which extends across the machine just beyond the cutter wheels 172. This gate is fixed on a shaft 206 which is mounted in bearings in the sub-frame 141. The shaft carries a lever arm 207 (Figs. 9 and 10) which is connected to a movable core 208 of an electric solenoid 209 which is actuated by the detector switches 202 through suitable electric circuits, which will be hereinafter explained.

The normal position of the gate 205 is shown in Figs. 8 and 9. Square sheets after being cut into blanks C pass over the top of the gate and are directed onto a continuously moving conveyor belt 211 which carries them to a suitable place of deposit. The belt operates over a pulley 212 mounted on a shaft 213 carried in bearings 214 formed in a stand 215 located adjacent the discharge end of the machine. A stop plate 216 secured to the stand adjacent the far side of the belt locates the blanks C on the belt as they pass from the cutter wheels 172.

If an out-of-square sheet B is detected, the detector switches 202, operate the solenoid 209 to rock the gate 205 into the position shown in Fig. 10. In this position of the gate, blanks C as they come from the cutter 172, are deflected downwardly as shown in Fig. 10 and are deposited into a bin 218 located in the bottom of the stand 215.

Reference now should be made to the portion of the wiring diagram at the right of Fig. 2. In this portion of the diagram the four detecting switches 202 are connected in series by wires 221. The first of the switches is connected by a wire 222 to the main lead wire 103 which leads from the generator 104. The last of the switches is connected by a wire 223 to a solenoid relay 224 having a movable core 225. The relay is also connected by a wire 226 to the main return wire 109 which connects with the generator.

When all four detector switches 202 are closed, by the detection of a square sheet B, electric energy flows from the generator 104 along this circuit and energizes the solenoid relay 224. Energizing of this relay shifts its movable core 225 and this closes two normally open switches 228, 229 which are connected to the core. Switch 228 is part of a holding circuit which includes a cam operated normally closed switch 231.

Since the greater number of sheets B which pass through the machine are good sheets, the holding circuit is incorporated in the apparatus to hold the gate 205 in its normal position to

prevent shifting of the gate for each sheet. For this purpose one side of the cam switch 231 is connected by a wire 232 to the lead wire 222. The other side of the cam switch is connected by a wire 233 to the switch 228. Switch 228 is also connected by a wire 234 to the wire 223.

The cam switch 231 is mounted on a side of the sub-frame 141 adjacent the gauge slide cam 176 and is actuated by a cam projection on the cam 176 in the same manner as the cam projection 118 on the cam 83, as shown in Fig. 7. This cam projection momentarily opens the cam switch 231 just prior to the closing of the detector switches 202. The cam switch closes again before the detector switches open and thus electric energy passing along this holding circuit maintains the solenoid relay 224 in an energized condition.

The switch 229 on the relay core 225 forms a part of a gate solenoid circuit which includes the gate solenoid 209. One side of the switch is connected by a wire 235 to the lead wire 222. The opposite side of the switch is connected by a wire 236 to the gate solenoid 209. The solenoid is also connected by a wire 237 to the return lead wire 226.

Hence when the switch 229 is closed by the energizing of the relay 224, electric energy from the generator 104 passes along this solenoid circuit and energizes the gate solenoid 209. It is this energy that maintains the solenoid 209 energized most of the time and thus maintains the gate 205 in its normal position as long as good sheets B are passing through the machine.

When an out-of-square sheet is detected and one or more of the detector switches 202 remain open when the cam switch 231 opens, all of the normal circuits are immediately broken and the gate solenoid 209 is de-energized. It is this action that shifts the gate 205 into sheet deflecting position (Fig. 10) as hereinbefore explained.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a sheet slitting machine, the combination of a conveyor for propelling sheets to be cut through the machine, gauging devices disposed adjacent the path of travel of the moving sheets for bringing the sheets into a predetermined position, detecting elements located adjacent said gauging devices and engageable with an edge of a sheet for detecting such an out-of-square condition that squared sheets of proper size cannot be cut from said sheet, and means operable by said detecting elements for discarding the out-of-square sheets from the machine.

2. In a sheet slitting machine, the combination of a conveyor for propelling sheets to be cut through the machine, gauging devices disposed adjacent the path of travel of the moving sheets for bringing the sheets into a predetermined position, detecting elements located adjacent said gauging devices and engageable with an edge of a sheet for detecting such an out-of-square condition that squared sheets of proper size cannot be cut from said sheet, electric switches operable by said detecting elements when an out-of-square sheet is detected, an electric solenoid connecting with and operable by said

switches, and a gate located in the path of travel of said sheets and operable by said solenoid to deflect out-of-square sheets from the machine.

3. In a sheet slitting machine, the combination of a conveyor for propelling sheets to be cut along a path of travel in one direction, an auxiliary conveyor for receiving cut sheets from the first conveyor and for propelling them in another direction, gauging devices disposed adjacent both paths of travel of the sheets for bringing the sheets into predetermined positions, detecting elements located adjacent said gauging devices for detecting such out-of-square sheets that squared sheets of proper size cannot be cut from said sheet, and means adjacent the discharge end of each conveyor and operable by the detecting elements of its conveyor for discarding from the machine out-of-square sheets detected on that conveyor.

4. In a sheet slitting machine, the combination of a plurality of conveyors disposed at angles to each other for propelling sheets to be cut along paths of travel extending in different directions, cutter wheels located adjacent each conveyor for trimming and cutting the sheets into a plurality of rectangular blanks, movable gate members adjacent each set of cutter wheels for guiding sheets from one conveyor to the next in line, gauging devices disposed adjacent each set of cutter wheels for bringing the moving sheets into a predetermined position prior to cutting, detecting elements located adjacent said gauging devices for detecting such out-of-square sheets that squared sheets of proper size cannot be cut from said sheet, and electric means operable by said detecting elements and connecting with said gate members for shifting the latter into a sheet deflecting position when an out-of-square sheet is detected thus discarding such a sheet from the machine.

5. In a sheet edge trimming machine, a first operation edge trimming unit having a longitudinal sheet guiding feedway thereon, a second operation edge trimming unit having a longitudinal sheet guiding feedway thereon disposed in a right angular relation to the first mentioned feedway and in position to receive partially trimmed sheets therefrom, sheet edge trimming equipment on the first operation unit, sheet edge trimming equipment on the second operation unit, means for feeding sheets over the first operation unit feedway and onto the other feedway, means for feeding sheets over the second operation feedway, a set of laterally reciprocable gages engageable with the sheets while moving to the first operation trimming equipment, a set of laterally reciprocable gages engageable with the sheets while moving to the second operation trimming equipment, the first operation gage set including two longitudinally spaced gage elements engageable with sheet edges at one side of the associated feedway and a single gage element engageable with sheet edges at the other side of said associated feedway intermediately of said two gage elements, and means for reciprocating said gage sets, and detecting means associated with said first and second operation units for detecting such out-of-square sheets that sheets of proper size cannot be produced therefrom by said units.

6. A sheet edge trimming machine structure as defined in claim 5 in which the single gage element which intermediately opposes the two longitudinally spaced gage elements is yieldably mounted so as to be displaceable by such out-of-square sheet.

7. In a sheet edge trimming machine, a first operation edge trimming unit having a longitudinal sheet guiding feedway thereon, a second operation edge trimming unit having a longitudinal sheet guiding feedway thereon disposed in a right angular relation to the first mentioned feedway and in position to receive partially trimmed sheets therefrom, sheet edge trimming equipment on the first operation unit, sheet edge trimming equipment on the second operation unit, means for feeding sheets over the first operation unit feedway and onto the other feedway, means for feeding sheets over the second operation feedway, a set of laterally reciprocable gages engageable with the sheets while moving to the first operation trimming equipment, a set of laterally reciprocable gages engageable with the sheets while moving to the second operation trimming equipment, said last mentioned feeding means including four feeding and rectifying elements yieldably engaging a sheet at four points in two pairs one pair engaging in laterally spaced relation at the advance previously trimmed edge of the sheet and the other pair engaging in laterally spaced relation adjacent the untrimmed edges of the sheet, and detecting means associated with said first and second operation units for detecting such out-of-square sheets that sheets of proper size cannot be produced therefrom by said units.

8. In a machine of the character described, a sheet edge trimming unit comprising a sheet guiding feedway, a sheet edge trimming equipment, means for feeding sheets to said trimming equipment, a set of laterally reciprocable gages engageable with the sheets while moving to the trimming equipment, and including two longitudinally spaced gage elements engageable with sheet edges at one side of the feedway and a single gage element engageable with sheet edges at the other side of the feedway intermediately of said two gage elements, means for reciprocating the gage elements into and out of contact with sheet edges, detecting means positioned adjacent said feedway for detecting such out-of-square sheets that sheets of proper size cannot be produced therefrom by said units, and means operable by said detecting means for discarding the out-of-square sheets from the machine.

9. A sheet edge trimming machine structure as defined in claim 8 in which the single gage element which intermediately opposes the two longitudinally spaced gage elements is yieldably mounted so as to be displaceable by such out-of-square sheet.

LYMAN L. JONES.
